IRON WORKS, OF WEST BERKELEY, CALIFORNIA, A CORPORATION OF CALIFORNIA.

AUTOMATIC BALANCE FOR CENTRIFUGAL PUMPS.

1,027,624.

Specification of Letters Patent.

Patented May 28, 1912.

Application filed September 18, 1911. Serial No. 649,895.

To all whom it may concern:

Be it known that I, ALBERT C. PAULSMEIER, citizen of the United States, residing at Alameda, in the county of Alameda and State of California, have invented new and useful Improvements in Automatic Balances for Centrifugal Pumps, of which the following is a specification.

My invention relates to centrifugal pumps, and pertains especially to end-thrust counterbalancing means therefor. In deep wells where these pumps are used extensively a great deal of difficulty has been met with by reason of the wear, caused on the 15 running joints of the runner and casing by the passage or leakage of the water, especially where the water carries any sand or grit. In fact, it has been found that where these pumps are operated at high 20 speed and working in muddy water that the joints will become so badly worn that it requires almost constant attention to keep the pump in balance. This is especially true where the surfaces of the running joints 25 are circumferential and parallel with the axis of the runner.

One purpose of the present invention is to construct the pump with the so-called running joints or leakage joints between the 30 space of uncontrolled pressure, and the space of variable pressure in the pump so that they will be approximately at right angles to the runner axis rather than parallel thereto as heretofore; whereby as wear takes 35 place the parts may automatically take up wear without destroying the automatic balance.

Another object is to provide means for making these wearing surfaces adjustable 40 so as to take up wear from time to time and keep the pump in proper balance.

Another object is to make the balance-ring of these pumps of such diameter, with respect to the suction inlet, that the difference in area between the two sides of the impeller or runner exposed to pressure will be sufficient to force the impeller away from the suction even though there may be the greatest possible vacuum acting in the direction of the suction.

A further object is to construct the runner and casing so that in the case of a vertical pump the suction inlet would be on the underside and central of the casing.

There are other objects and advantages 55 which will be apparent hereinafter.

The invention consists of the parts and the construction and combination of parts as hereinafter more fully described and claimed, having reference to the accompanying drawings, in which—

Figure 1 is a sectional view showing a vertical pump installation. Fig. 2 is a fragmentary section showing a modification. Fig. 3 is a similar view of another modification. Fig. 4 is an enlarged fragmentary view of the removable wearing ring.

In Fig. 1 which represents a vertical shaft pump installation for use in deep wells, A is the pump casing having the 70 upper shaft cover 2. 3 is an impeller, having the radial discharge passages 4. 5 is a suction inlet. 6 is the volute of the case into which the impellers discharge. 7 is the discharge pipe. 8 is a shafting from pump to 75 top of well of suitable length, and by which shafting the impeller is driven by any suitable means, as an electric motor not here shown. 9 is the supporting frame to which the pump is bolted or otherwise secured, and 80 10 is a spacing bar for centering the pump. 11 is an annular space constituting a variable pressure chamber and distinguishing from the space 12 on the underside of the runner and all that other space outside the 85 runner which is subjected to the uncontrolled pressure of the discharge column.

The present invention relates especially to the means for controlling the admission of water from the zone of uncontrolled pressure outside the runner into the "variable pressure chamber" 11, and the subsequent escape of this water from the variable pressure chamber back into the interior of the runner; together with the means for providing for differential of pressures on the two sides of the runner whereby the pressure on the suction side of the runner, that is to say, the pressure in space 12, is always sufficient to force the impeller away from 100 the suction even though there may be the greatest possible vacuum tending in the opposite direction or toward suction. In order to accomplish these ends the under or suction side of the runner has a hollow hub 13 105 forming a running joint, with an inwardly extending flange 14 which is carried by a removable ring-plate 15. As wear takes

place on the contiguous surfaces 14—13 replacements can easily be made by taking off the ring-plate 15 and substituting a new one with a flange 14 of proper size. On 5 the opposite side of the runner I employ a balance-ring 16 which is approximately of the same diameter as the impeller, and is so arranged and constructed that it will present a wearing surface substantially at right 10 angles to the axis of the impeller and ordinarily will have a running contact with a like parallel surface or ring 17 at or adjacent to the edge of the impeller. This balance-ring 16 may be made angular in 15 cross section and be adjustable by suitable means as the bolts 18, or it may be fixed to the casing or casing cover by suitable means as the bolts 18', Fig. 2.

The complementary ring 17 on the runner 20 overlaps the balance-ring 16, which latter occupies an annular channel or space between the ring 17 and the adjacent face of the runner. The tendency of the suction, and in the case of a vertical pump, the 25 weight of the shafting and other moving parts, is to force the runner down until the revolving ring 17 on the runner is in running contact with the fixed balance-ring 16 on the casing. Opposed to this downward 30 thrust, due to suction and gravity, is the upthrust, due to the weight of the column of water in the discharge pipe of the pump. The length of this discharge pipe or height 35 to which the water is forced by the pump is commonly called the "head", or "head pumped against", and this "head" varies with the depth of the water in the well or the depth of submergence of the pump. This upthrust, due to the weight of the column 40 of water in the discharge, exerts itself on the underside of the impeller in chamber 12, and the area on the underside of the runner exposed to this upthrust is great enough as before stated in my improved construction, to force the impeller always away 45 from the suction; this being possible by making the balance-ring 16 of very much larger diameter than the diameter of the suction inlet 5. As a result of this upthrust pressure or 50 back pressure of the discharge column 7 a leakage takes place into the chamber 11 between the rings 16—17. In order to control this upthrust on the impeller, I provide the following means for relieving the accumulation 55 of pressure in the variable pressure chamber 11:

The hub of the runner opposite the suction inlet is made hollow, or otherwise constructed, to provide relief ports 19 which 60 form communicating passages between the variable pressure chamber 11 and the radial vanes 4; these ports 19 entering the vanes 4 in such a manner as to point partially in the direction of the water pumped through the 65 vanes 4.

In order to throttle the ports 19 I have shown in Fig. 1 an adjustable plug 20 which may be moved in and out, in the line of the shaft 8, and toward or from the hub of the runner according to the leakage pressure between the parts 16—17, or the variations of "head pumped against." This plug 20 is hollow and surrounds the shafting 8 and forms a packing-box with which the gland or bushing 21 co-operates. In cheap pumps where it is not desired to make the plug adjustable it may form a fixed part of the cover, as shown at 20' Fig. 3.

In Fig. 2 I have shown the plug in the form of a stationary, renewable, balance-plug ring 20'; this plug ring being held in place by suitable means such as the lock screw 22. In all cases the principle is the same; the throttling of the ports 19 being accomplished by the movement of the runner toward the plug 20 or 20' or 20", or the adjacent wall of the cover 2. When the runner moves toward the plug 20 or cover 2, it carries the balance-ring 17 farther away from the balance-ring 16, thereby passing more water 80 into the variable pressure chamber 11 and allowing less water to pass out through the ports 19. When the pressure thus accumulated in chamber 11, overbalances the opposed pressure in the space 12 the runner tends to move toward the suction inlet side, thereby closing the leakage space between the rings 16—17 and opening wider the communication between chamber 11 and ports 19 and giving relief to the pressure in the chamber 11 until a state of balance is restored.

Manifestly, the foregoing principles are applicable both for vertical and horizontal installations.

By having all wearing surfaces normal to the runner, all tendency to excess leakage, due to wear of the running parts, is automatically compensated for; and whenever any of the parts show a great deal of wear, such for instance as the rings 16, 17 or 20", or plug 20, the same may be quickly replaced at small expense.

Having thus described my invention, what I claim and desire to secure by Letters Patent is—

1. An automatic, hydraulic counterbalance for a centrifugal pump, consisting in the combination of an incased runner, having a central suction inlet and a peripheral discharge; a case in which the runner is revoluble; the runner carrying on one side an annular flange normal to the runner axis; the case bearing a corresponding flange toward and from which the runner-flange is movable according to the shifting of the runner axial in the case; said flanges and the runner and casing inclosing a variable pressure chamber on the side opposite to the suction, and which chamber is in communi- 120 125 130

- cation with the pump discharge between said flanges, said variable pressure chamber having a discharge back into the runner; and means controlled by the shifting of the 5 runner to vary the discharge from the variable pressure chamber into the runner, and said last-named means constructed and arranged so that, as the flanges move closer together to shut off supply of water from the pump discharge into the variable pressure chamber, the discharge opening from the variable pressure chamber back into the runner is increased; and vice versa, when the flanges move apart to increase the water 10 supply to the variable pressure chamber from the pump discharge, the discharge opening from the variable pressure chamber back into the runner is decreased.
2. In a centrifugal pump, the combination 15 of a case having a central inlet and a peripheral discharge, a shaft, an impeller in the case on the shaft, means formed by the case and the side of the impeller opposite the suction to inclose a variable pressure chamber 20 receiving leakage water under pressure from the discharge through the running joint between the impeller and case, said running joint consisting of two annular opposed coacting surfaces which are normal to the axis 25 of the impeller, whereby thrust in one direction carries the two surfaces toward each other and vice versa thrust in the opposite direction carries them farther apart, said variable pressure chamber having a relief 30 discharge back into the impeller, and means forming a variable throttle for said relief discharge, last named means adapted to automatically increase the available area of the relief discharge in response to the approach of said opposed surfaces, and to reduce the area of the relief discharge as the space between said surfaces increases.
3. In a centrifugal pump, the combination 35 of a case having a central inlet and a peripheral discharge, a shaft, an impeller in the case on the shaft, means formed by the case and the side of the impeller opposite the suction to inclose a variable pressure chamber 40 receiving leakage water under pressure from the discharge through the running joint between the impeller and case, said running joint consisting of two annular opposed coacting surfaces which are normal to the axis 45 of the impeller, whereby thrust in one direction carries the two surfaces toward each other and vice versa thrust in the opposite direction carries them farther apart, said variable pressure chamber having a relief discharge back into the impeller, and means 50 forming a variable throttle for said relief discharge, last named means comprising a movable plug, said plug co-acting with the impeller to increase the available area of the relief discharge simultaneously with the approach of said opposed surfaces, and to re-
- duce the area of the relief discharge in unison with the recession of said surfaces.
4. In a centrifugal pump, the combination 55 of a case having a central inlet and a peripheral discharge, a shaft, an impeller in the case on the shaft, means formed by the case and the side of the impeller opposite the suction to inclose a variable pressure chamber receiving leakage water under pressure from the discharge through the running joint between the impeller and case, said running joint consisting of two annular opposed coacting surfaces which are normal to the axis of the impeller, whereby thrust in one direction carries the two surfaces toward each other and vice versa thrust in the opposite direction carries them farther apart, and said variable pressure chamber having a relief discharge back into the impeller, one of said 60 surfaces comprising a ring on the impeller, and the other a complementary ring on the case, and means whereby one of said rings may be adjusted relatively to the other ring from a point outside the case.
5. In a centrifugal pump, the combination 65 of a case having a central inlet and a peripheral discharge, a shaft, an impeller in the case on the shaft, means formed by the case and the side of the impeller opposite the suction to inclose a variable pressure chamber 70 receiving leakage water under pressure from the discharge through the running joint between the impeller and case, said running joint consisting of two annular opposed coacting surfaces which are normal to the axis of the impeller, whereby thrust in one direction carries the two surfaces toward each other and vice versa thrust in the opposite direction carries them farther apart, and said variable pressure chamber having a relief discharge back into the impeller, one of said 75 surfaces comprising a ring on the impeller, and the other a complementary ring on the case, and means whereby one of said rings may be adjusted relatively to the other ring from a point outside the case.
6. A vertical centrifugal pump, comprising 80 a case, and a runner with a vertical shaft, the runner having an unrestricted central suction inlet on its underside in free communication with the runner vanes and the runner supported on the lower end of the shaft, the hub of the runner around the suction having a running joint with the case, which running joint is in a cylindrical 85 plane concentric with the shaft, the opposite side of the runner having a running joint with the case, but which running joint is at right angles to the shaft, said last named running joint inclosing a chamber which leads back through the hub of the runner into the suction side of the latter, said running joint opposite the suction being of sufficiently greater diameter than the running 90 joint on the suction side as to cause the pressure

sure in the pump discharge to force the runner in the direction opposite to the suction inlet no matter how great the vacuum is toward the suction, and means forming a 5 variable throttle for the discharge from said chamber back through the hub of the runner, said means operating to increase the available area of the discharge simultaneously with the closing of the second-named joint, and reducing the area of the discharge simultaneously with the opening of said joint.

7. A centrifugal pump, comprising a case, and a runner with a shaft, the runner having an unrestricted central suction inlet in free communication with the runner vanes and the runner supported on the end of the shaft, the hub of the runner around the suction having a running joint with the case, 15 which running joint is in a cylindrical plane concentric with the shaft, the opposite side of the runner having a running joint with the case, but which running joint is at right angles to the shaft, said last named running

joint inclosing a chamber which leads back 25 through the hub of the runner into the suction side of the latter, said running joint opposite the suction being of sufficiently greater diameter than the running joint on the suction side as to cause the pressure in 30 the pump discharge to force the runner in the direction opposite to the suction inlet no matter how great the vacuum is toward the suction, and means forming a variable throttle for the discharge from said chamber back through the hub of the runner, said means operating to increase the available area of the discharge simultaneously with the closing of the second-named joint, and reducing the area of the discharge simultaneously with the opening of said joint.

In testimony whereof I have hereunto set my hand in the presence of two subscribing witnesses.

ALBERT C. PAULSMEIER.
